SLICING MACHINE

Henry Thomas, Chingford, England, assignor to
U. S. Slicing Machine Company, La Porte, Ind.,
a corporation of Indiana

Application June 22, 1944, Serial No. 541,539
In Great Britain March 23, 1943

9 Claims. (Cl. 146—102)

This invention relates in general to slicing machines and more particularly to slicing machines of the type having an inclined rotary slicing knife and an inclined reciprocable substance holder or support providing for the feeding of substance to the cutting plane of the knife by gravity.

An object of this invention is to provide compact, safe, simple and efficient means in such a machine for supporting the substance holder in relation to the base of the machine so that it may be quickly and effectively shifted from an operative setting to an inoperative setting to provide unobstructed access to otherwise inaccessible portions of the machine to enable them to be adjusted, repaired, removed, replaced, and cleaned.

Another object of this invention is the provision of novel means in such a machine for pivotally supporting a substance holder so that it may be swung conveniently from an operative setting in which the holder is supported at an inclination, usually complementary to the inclination of the slicing knife, to an inoperative setting in a predetermined position of adjustment in its reciprocal travel, preferably at an end of its stroke remote from the cutting plane of the knife.

A further object of the invention is the provision of novel means in such a machine for enabling pivotal movement of the substance holder into and out of operative relation with the knife in a direction transverse to the direction of reciprocal movement of the holder.

Other objects of the invention include the provision of novel means in such a machine for anchoring the substance holder against reciprocal movement in relation to the cutting plane of the knife while the holder is in an inoperative setting; the provision of novel means in such a machine for limiting pivotal movement of the substance support; the provision of novel means in such a machine for preventing the pivoting of the substance holder from an operative setting to an inoperative setting except when the holder is in a predetermined position in relation to the cutting plane of the knife; and the provision in such a machine of cooperative means on the substance holder or support and the base of the machine including guide means mounted on the base and arranged in angular spaced relation with the plane of rotation of the knife and a supporting arm mounted on the guide means for pivotal and for sliding movement in relation thereto and operatively connected with the sub-

stance support, and means on the base and arranged in cooperative relation with the cooperative means on the substance support for preventing reciprocal movement of the substance support when it is out of operative relation with the knife.

Additional objects, advantages and capabilities inherent in this invention will become readily apparent from the description thereof which follows.

This invention further resides in the combination, construction and arrangement of parts illustrated in the accompanying drawings, and while there is shown therein preferred embodiments of the invention, it is to be understood that the same are susceptible of modification and change without departing from the spirit of the invention.

The accompanying drawings illustrate a selected embodiment of the invention, and the views therein are as follows:

Fig. 1 is an end elevation, partially in section, of a slicing machine embodying the invention;

Fig. 2 is an enlarged fragmentary view, partially in section, of portions of the machine shown in Fig. 1;

Fig. 3 is a fragmentary side elevation of the machine shown in Fig. 1, looking to the left in that figure;

Fig. 4 is a fragmentary end elevation of a machine embodying a modified form of the invention, partially in section;

Fig. 5 is a detail view, partially in section, of portions of the machine shown in Fig. 4.

The particular machine herein disclosed for the purpose of illustrating the invention, as shown in Figs. 1, 2 and 3, comprises a base 10 including a casing 11 which is generally closed. A knife supporting bracket 12 is mounted on the base 10 and angularly arranged in relation to the base, being inclined upwardly and rearwardly. A rotary slicing knife 13, circular in form, is journalled in the bracket 12 and operatively connected through a pulley and belt driving assembly 14 with a worm gear 15 mounted on the drive shaft of the electric motor 16, which is supported on the base 10 within the casing 11. An adjustable gauge plate 17 is supported on the bracket 12 in cooperative relation with the knife 13 and is encased in a guard 18 including a mask 19 also supported on the bracket 12. The gauge plate 17 is adjustable through a handle 20 rotatably mounted in the casing 11 and connected with the gauge plate by conventional means, not shown.

A track or generally rectangular guide rod 21 is

provided on a rearwardly facing surface of the casing 11 and a generally cylindrical guide rod 22 is provided within and adjacent the front of the casing 11 in generally parallel relation with the track 21, opposite ends of the rod 22 being suitably mounted in opposite end portions of the casing 11.

A substance holder or support 23 of trough form and approximate L-section is secured to a supporting arm 24 adjacent one end thereof. The supporting arm 24 has a curved extension including a generally reverse end portion 25 which extends through an elongated slot 26 in the front wall of the casing 11 in spaced relation with the rod 22. The portion 25 terminates in a bearing or carriage 27 which is slidably and pivotally mounted on the guide rod 22. A roller 28 is rotatably mounted on the supporting arm 24 adjacent its end portion remote from the portion 25 for rolling engagement with the track 21 when the substance holder or support is in its operative setting or position, as shown in full lines in Fig. 1. The arrangement of the substance holder 23, the supporting arm 24, and their associated parts, is such that the substance holder, in its operative setting, extends in a direction normal to the cutting plane of the knife, the inclination of the holder and the knife, as shown in Fig. 1, being approximately 45° to the horizontal. The holder and its supporting arm 24 are reciprocal by means of a handle 29 provided on the supporting arm along the guide rod 22 and the track 21 in this angular relation. The holder 23, the supporting arm 24, the guides 21 and 22 and their associated parts, furthermore, are arranged so as to provide for such a distribution of their mass, together with the mass of any substance carried by the holder 23, that the combined weight of the holder, its support and the substance borne by it will be carried mainly by the roller 28 and the track 21, thus providing for freely sliding movement of the bearing 27 along the guide rod 22.

In operating the machine illustrated in Figs. 1, 2 and 3, the operator will normally occupy a stance facing the view shown in Fig. 1 with his right hand gripping the handle 29 and his left hand in position convenient to the usual slice receiving platform 30 provided on the base 10.

In operating the machine illustrated in Figs. 1, 2 and 3, the operator will normally occupy a stance facing the view shown in Fig. 1 with his right hand gripping the handle 29 and his left hand in position convenient to the usual slice receiving platform 30 provided on the base 10.

The elongated slot 26 is generally of sufficient width to enable free passage along it of the portion 25 of the supporting arm 24, with provision of the downwardly extending enlarged portion or recess 31 adjacent one end thereof for receiving the portion 25 upon pivotal movement of the holder 23 and the supporting arm 24 to the position indicated in dotted lines in Fig. 1, when it is desired to shift or swing the holder from operative setting or position to inoperative position. The recess 31 serves to prevent sliding of the holder and its supporting arm along the guide rod 22. In its inoperative position the holder is entirely removed or displaced from the slicing assembly, that is, the knife, the gauge plate and associated parts, so that safe and ready access may be had to the holder and parts of the machine inaccessible when the holder is in its operative setting for cleaning the parts and other purposes.

In order to prevent inadvertent displacement

of the holder 23 from its operative setting a spring-loaded hinged plate 32 may be secured on the base 10 normally to be received within the recess 31 and to serve as a closure therefor. When it is desired to shift the holder 23 from its operative to its inoperative setting, the operator will first press the plate 32 inwardly against the action of its associated spring and thereafter shift the holder to inoperative position, a surface of the portion 25 of the supporting arm 24 engaging the plate 32 and displacing it to the position indicated in dotted lines in Figs. 1 and 2. Upon return of the holder 23 to operative position, the plate 32 will be returned to normal position within the recess 31 by the operation of its associated spring.

In the modified form of the invention shown in Fig. 4, instead of using a roller and track support for the holder 23 at the rear of the casing 11, as shown in Fig. 1, an auxiliary guide rod 33 is mounted on the base 10 in parallel spaced relation with the guide rod 22. The portion 25 of the arm 24 is omitted and the corresponding end portion of the arm 24 is hinged at 34 to an angulated slide member 35 which is provided with a bearing 35a slidably mounted on the guide rod 22 and with a fork 26 spanning the auxiliary guide rod 33. The hinge connection between the arm 24 and the slide 35 is such as to permit the arm 24 and the holder 23 to be pivoted in a manner similar to that described in connection with the arrangement of Figs. 1, 2 and 3, but the end of the arm 24 has abutting relationship with the part to which it is pivoted to hold the arm normally in the position shown in Fig. 4. In order to prevent displacement of the holder 23 from its operative setting or position to its inoperative setting or position, except at a predetermined position of adjustment in its range of reciprocal movement, an opening 37 is provided in the base 10 for receiving a spring pressed pin 38 which is mounted in the slide member 35 in cooperative spaced relation with a projection 39 provided on the arm 24 adjacent the hinge 34. The arrangement is such that upon swinging of the arm 24 to the right, viewing Figs. 4 and 5, the projection 39 will engage the head of the pin 38 and press its opposite end into the opening 37, provided that the holder is in the appropriate position so that the pin registers with the opening; otherwise when it is attempted to swing the holder, the pin will strike the wall of the base and obstruct displacement of the holder. It will be readily apparent that the pin 38 also functions to secure the substance holder against sliding movement when displaced into its inoperative setting with the pin received within the opening 37.

Changes may be made in the form, construction and arrangement of the parts without departing from the spirit of the invention, and the right is hereby reserved to make all such changes as fairly fall within the scope of the following claims.

The invention is hereby claimed as follows:

65 1. A slicing machine comprising a base, a slicing knife mounted on the base for rotary cutting movement in a plane disposed in angular spaced relation with the base, an adjustable gauge plate for determining thickness of slice, a substance support mounted on the base for reciprocal movement in predetermined angular relation to the cutting plane of the knife, cooperative means on the support and the base operable to enable pivotal movement of the support into and out of operative relation with the knife, the

70

75

said cooperative means comprising guide means mounted on the base and arranged in angular spaced relation with the plane of rotation of the knife and a supporting arm mounted on the guide means for pivotal and for sliding movement in relation thereto and operatively connected with the substance support, and means on the base and arranged in cooperative relation with the cooperative means on the substance support for preventing the said reciprocal movement of the substance support when the substance support is out of operative relation with the knife.

2. A slicing machine comprising a base, a slicing knife mounted on the base for rotary cutting movement in a plane disposed in angular spaced relation with the base, an adjustable gauge plate for determining thickness of slice, a substance support mounted on the base for reciprocal movement in predetermined angular relation to the cutting plane of the knife, cooperative means on the support and the base selectively operable to enable pivotal movement of the support into and out of operative relation with the knife, the said cooperative means comprising guide means mounted on the base and arranged in angular spaced relation with the plane of rotation of the knife and a supporting arm mounted on the guide means for pivotal and for sliding movement in relation thereto and operatively connected with the substance support, means on the base and arranged in cooperative relation with the cooperative means on the substance support for limiting pivotal movement of the substance support, and means on the base and arranged in cooperative relation with the cooperative means on the substance support for preventing the said reciprocal movement of the substance support when the substance support is out of operative relation with the knife.

3. A slicing machine comprising a base, a slicing knife mounted on the base for rotary cutting movement in a plane disposed in angular spaced relation with the base, an adjustable gauge plate for determining thickness of slice, a substance support mounted on the base for reciprocal movement in predetermined angular relation to the cutting plane of the knife, cooperative means on the support and the base operable to enable pivotal movement of the support into and out of operative relation with the knife, the said cooperative means comprising guide means mounted on the base and arranged in angular spaced relation with the plane of rotation of the knife and a supporting arm mounted on the guide means for pivotal and for sliding movement in relation thereto and operatively connected with the substance support, means on the base and arranged in cooperative relation with the cooperative means on the substance support for limiting pivotal movement of the substance support, and manually operable means on the base and arranged in cooperative relation with the cooperative means on the substance support for preventing the said reciprocal movement of the substance support when the substance support is out of operative relation with the knife.

4. A slicing machine comprising a base, a slicing knife mounted on the base for rotary cutting movement in a plane disposed in angular spaced relation with the base, an adjustable gauge plate for determining thickness of slice, a carriage mounted on the base for reciprocal movement in relation to the cutting plane of the knife, a substance support mounted on the carriage

for reciprocal movement in predetermined angular relation to the cutting plane of the knife, cooperative means on the support and the carriage operable to enable pivotal movement of the support into and out of operative relation with the knife, and cooperative means on the carriage and the base for preventing the said reciprocal movement of the support when the support is out of operative relation with the knife.

5. A slicing machine comprising a base, a slicing knife mounted on the base for rotary cutting movement in a plane disposed in angular spaced relation with the base, an adjustable gauge plate for determining thickness of slice, a carriage mounted on the base for reciprocal movement in relation to the cutting plane of the knife, a substance support mounted on the carriage for reciprocal movement in predetermined angular relation to the cutting plane of the knife, cooperative means on the support and the carriage operable to enable pivotal movement of the support into and out of operative relation with the knife, cooperative means on the carriage and the base for preventing the said reciprocal movement of the support when the support is out of operative relation with the knife, and means on the support for operating the last mentioned cooperative means.

6. A slicing machine comprising a base, a slicing knife mounted on the base for rotary cutting movement in a plane disposed in angular spaced relation with the base, an adjustable gauge plate for determining thickness of slice, a carriage mounted on the base for reciprocal movement in relation to the cutting plane of the knife, a substance support mounted on the carriage for reciprocal movement in predetermined angular relation to the cutting plane of the knife, cooperative means on the support and the carriage operable to enable pivotal movement of the support into and out of operative relation with the knife, and cooperative means on the carriage and the base for preventing the said reciprocal movement of the support when the support is out of operative relation with the knife, the last mentioned cooperative means comprising keeper means on the base and spring actuated latch means on the carriage and arranged in cooperative relation with the keeper means.

7. A slicing machine comprising a base, a slicing knife mounted on the base for rotary cutting movement in a plane disposed in angular spaced relation with the base, an adjustable gauge plate for determining thickness of slice, a substance support mounted on the base for reciprocal movement in predetermined angular relation to the cutting plane of the knife, cooperative means on the support and the base operable to enable pivotal movement of the support into and out of operative relation with the knife, and means on the base for preventing pivotal movement of the support except when the support is in a predetermined position of adjustment in relation to the cutting plane of the knife.

8. A slicing machine comprising a base, a slicing knife rotatably mounted on said base, motive means operatively connected with said knife to drive the knife, a rod carried by the base, a bearing sleeve slidable on the rod, a substance support connected to said bearing sleeve, said substance support being mounted above said base for to-and-fro reciprocation in a rectilinear path parallel to the cutting plane of the knife to convey substance into slicing engagement with said

knife, said substance support being pivotally mounted on an axis parallel to the cutting plane and on the side thereof which is remote from the knife so that the support may be swung to an inoperative position in a direction perpendicular to the knife cutting plane and away therefrom to bare the upper surface of the base, and means to prevent such pivotal movement of the support to inoperative position except when the support is at a predetermined position with respect to the base.

9. A slicing machine comprising a base, a slicing knife rotatably mounted on said base, motive means operatively connected with said knife to drive the knife, a rod carried by the base, a bearing sleeve slidable on the rod, a substance support connected to said bearing sleeve, said substance support being mounted above said base

for to-and-fro reciprocation in a rectilinear path parallel to the cutting plane of the knife to convey substance into slicing engagement with said knife, said substance support being pivotally mounted on an axis parallel to the cutting plane and on the side thereof which is remote from the knife so that the support may be swung to an inoperative position in a direction perpendicular to the knife cutting plane and away therefrom to bare the upper surface of the base, means to prevent such pivotal movement of the support to inoperative position except when the support is at a predetermined position with respect to the base, and locking means to lock said support in said predetermined position and preventing reciprocation of said support when the support is in locked inoperative position.

HENRY THOMAS.
